UNITED STATES PATENT OFFICE.

CHARLES M. HOLDEN, OF SAN FRANCISCO, CALIFORNIA.

DYEING-COMB.

1,172,889.

Specification of Letters Patent. Patented Feb. 22, 1916.

Application filed November 1, 1915. Serial No. 59,066.

To all whom it may concern:

Be it known that I, CHARLES M. HOLDEN, a citizen of the United States, residing at San Francisco, in the county of San Francisco and State of California, have invented new and useful Improvements in Dyeing-Comb, of which the following is a specification.

This invention relates to improvements in combs used for dyeing purposes, and the object of the invention is to provide a comb by which a dyeing liquid can be distributed upon the head of the wearer uniformly and with no discomfort and in the exact locality desired, from which the dye can be discharged as close to the scalp of the head, as desired, which will not waste the dye, which can be easily taken apart and the parts thereof cleaned and reassembled, and which can be easily operated.

In the accompanying drawing, Figure 1 is a side view of the dyeing comb; Fig. 2 is a longitudinal sectional view thereof; Figs. 3 and 4 are cross sectional views on the lines 25 3—3 and 4—4 of Fig. 1 respectively.

Referring to the drawing, 1 indicates a hollow handle, which is of a general cylindrical form, but one end of which has an enlarged cylindrical extension 2 to form a receptacle for a cylindrical vessel 3 of rubber, said extension being still farther extended on the side opposite to the handle to form a somewhat narrow receptacle 4 for a presser piece 6. The extension 4 is cut away through its outer edge, as shown at 7, to permit of the rounded outer edge of the preser piece to be presesd inwardly by the thumb of the operator, and, when so pressed inwardly, the inner side 8 of the presser piece, which is extended laterally so as to be of greater width than the presser piece, and has a concave outer surface, is pressed against the cylindrical surface of the rubber reservoir, and compresses said reservoir, forcing outwardly the liquid dye contained within the same. The outer end of the reservoir is closed, but the inner end thereof contains a metallic neck 9, from which leads a small metallic conduit 11, around which is one end of a rubber tube 12, the other end of said tube encircling the open end of a metallic flat tube 13, the other end of which is closed. Said metallic tube 13 is contained within a piece 14 of folded cloth, from the 55 adjacent edges of which extend short lengths

15 of warp, the weft having been removed from said lengths, said warp being composed of comparatively stiff material such as horse hair. The cloth is contained in a channel-shaped metal holder 16, being held 60 in place in said holder by U-shaped pieces 17 of stout wire. Said holder is contained within a comb 18 consisting of pieces 19 of wire doubled, the free ends of which are secured to metallic strips 21, secured in opposite sides of the handle 22, which at this end is made channel-shaped. Said holder 16 is retained in said comb partly by means of hooks 23 and partly by a screw 24, screwed through the back of the handle and into the 65 back of said holder, and a spring 25 coiled around the screw normally presses said holder away from the handle. A loop 26, attached at its free end to the side strips 21, serves to suspend the comb from any suitable support. The bend of the wires 19 is somewhat sharp, but not sharp enough to injure the scalp of the user.

In the inner edge of the metal tube 13, or that next the ends of the teeth of the comb, 80 are small perforations 27, through which the liquid dye can pass from said metal tube into the space between the bristles 15 extending from the folded cloth.

Upon pressing the presser piece 6 with the 85 thumb the liquid dye is forced through the small perforations 27 into the space between the bristles 15 and moistens them so that, when the wire comb is drawn through the hairs of the head, the hairs are moistened 90 with the liquid dye. For dyeing the outer portions of long hair the screw is screwed into the back of the holder, so that the holder is withdrawn from the point of the teeth, and for dyeing the hair close to the 95 scalp the screw is screwed in the opposite direction so that the bristles are forced into the points of the teeth of the comb.

It will be observed that by my improved construction I provide a comb and brush in 100 one instrument.

I claim:—

1. A dyeing comb having a handle and wire teeth, and a liquid distributer contained within the teeth and formed of dou- 105 bled fabric, the weft of which is removed at the edges, the exposed warp being of stiff material to form bristles.

2. A dyeing comb having a handle and teeth, a liquid distributer contained within 110

the teeth, a perforated metallic tube contained within the distributor, a compressible reservoir communicating with said tube and supported upon the handle of the comb, and
5 means for adjusting the distributor to and from the points of the teeth.

In testimony whereof I have hereunto set

my hand in the presence of two subscribing witnesses.

CHARLES M. HOLDEN.
